S. p. A., Milan, Italy

Application June 4, 1956, Serial No. 41,745

Term of patent 14 years

(Cl. D70—1)

FIG. 1

FIG. 2

Figure 1 is a perspective view of a sewing machine head showing my new design.

Figure 2 is a fragmentary end view of a sewing machine head.

The characteristic features of my design reside in the portions shown by means of full lines in the drawing. The side of the sewing machine head, not illustrated, is conventional.

I claim:

The ornamental design for a sewing machine head, as shown and described.
